CLAIM

The ornamental design for a swaddle, as shown.

DESCRIPTION

FIG. 1 is a front view showing my new design for a swaddle;
 FIG. 2 is a back view thereof;
 FIG. 3 is a front view thereof showing the swaddle in use
 and in a partially folded condition; and,
 FIG. 4 is a front view thereof showing the swaddle in use
 and in a fully folded condition.

The broken lines shown in the drawings illustrate stitching
 and environmental structure and form no part of the claimed
 design.
